UNITED STATES PATENT OFFICE

GEORGE A. SHOEMAKER AND ELIAS C. HOLLAND, OF BENTON HARBOR, MICHIGAN, ASSIGNEES TO METAL SECTIONAL FURNITURE COMPANY, OF PORTLAND, MAINE, A CORPORATION.

TEMPORARY BINDER.

No. 921,012.

Specification of Letters Patent.

Patented May 11, 1909.

Application filed January 18, 1907. Serial No. 352,945.

To all whom it may concern:

Be it known that we, GEORGE A. SHOEMAKER and ELIAS C. HOLLAND, citizens of the United States, and residents of the city of Benton Harbor, in the State of Michigan, have invented certain new and useful Improvements in Temporary Binders; and we do hereby declare the following to be a full and complete description of the same.

10 Our invention relates particularly to that class of temporary binders which have a varying holding capacity, and our invention resides in the special features described herein, reference being had to the accompanying drawings.

In the drawings, Figure 1 shows a perspective view of our binder. Fig. 2 shows the binding edge of one of our leaves. Fig. 3 shows a sectional view of our binder lock taken perpendicularly through the line of the binding posts of Fig. 1. Fig. 4 is a plan view of the bottom side of the binding cover of our binder. Fig. 5 is a detail showing the locking mechanism. Fig. 6 is a further detail of the same and Fig. 7 a detail of further construction of said binder.

More particularly described A, and A¹, represent the binding bars of our binder and X, and X¹, the covers of the binder attached to the said binding bars respectively.

A¹, represents the bottom bar of our binder to which the binding posts B B are rigidly attached and may be of any suitable form or material.

35 A, represents the locking bar of our binder and is suitably perforated to slide upon the binding posts B B. The locking bar A, is constructed as follows: A channeled bar a, is provided, fitted with a channel a¹, within which lies the lock mechanism of the binder. A plate a², is designed to cover the said channel, a¹, being secured from the underside of the bar, a by the screws a³. Within the channel or recess a¹, we place two lever arms 40 C C lying opposed to each other and provided at their inner ends with slots c³, and formed at their outer ends into hooks c² c², which hooks lie opposed to and are intended to engage with the binding posts B B. Midway of the lever arms they are slotted at c⁴ c⁴ through

which slots pass rivets a⁴ a⁴ which are attached at their opposite ends to the bar a¹ and the plate a², respectively. Between the inner ends of the lever arms C C and co-operating with the said arms, we provide a yoke 55 C¹, which is provided with lugs c⁴ c⁴ which engage the slots c³ c³ of the arms C C. Within the yoke C¹, we provide an eccentric, one which is rotatably secured to the plate a², by the screw c⁶, and which at its upper end projects beyond the outer surface of the bar a, and is fitted with a key head c⁷. It is designed that the rotation of the eccentric moves the yoke C¹ laterally within the said locking bar A and thereby engages and disengages the outer ends of the levers C C with the binding posts B B, the rivets a⁴ a⁴ acting as fulcrums for said levers. The slots c⁴ c⁴ permit the longitudinal movement of the said levers to care for any imperfection in the 60 mechanical construction or gaging of the parts.

In order to prevent the complete revolution of the eccentric and thereby permit in the locking movement the turning of the 75 eccentric beyond the locking point, we provide a small stud c⁵ attached to the under side of the said eccentric c, which stud moves within a semi-circular slot in the plate a² as shown at Fig. 4.

We provide a permanent and durable means of attaching the covers X and X¹ to the binding bars A A¹, described as follows: Upon the bar a, we provide contiguous therewith and projecting forward beyond the forward edge of said bar, the ears, E E E, which we perforate longitudinally. To these perforated ears we attach a perforated metal strip E¹, by means of a hinge pin, e. The covers of the binder X and X¹, consisting of cloth 85 board, tar board or other book binders' material, are built upon and around these metal strips E¹, the perforations e¹ e¹ serving to hold the binding materials in place. The finishing leather or other covering, H, is 90 placed around and over covers X and X¹, and the binding bars A and A¹ as one piece, the hinges at the ears E, showing as in Fig. 1 of the drawings.

For the purpose of preventing the scratch-

ing or marring of desks or tables, we provide means of protecting the same from the metal corners of the binding bars A and A¹ by placing thereon raised corners of rubber or 5 other resilient material, the detail of which rubber corner is shown at Fig. 7. We provide these corners in the following manner: An angle of metal is cut from the corner of the metal bar a, and the rubber piece D, cut 10 to fit said angle and project beyond the outer surface of the bar, is fitted upon said angle. It is held in place by a headed plug d¹, thrust through said corners D, and engaged from below by a screw d, which passes through the 15 metal bar A. Upon the binding posts B B are placed the ball caps b, b which are larger than the perforations of the locking bar A, through which the binding posts pass and will not permit the removal of the locking 20 bar A, from the posts B B. The leaves therefore to be used in the binder must be so constructed that they may be inserted and removed without passing over the ends of the posts B B. In order to accomplish this 25 we provide the leaves F, as shown at Fig. 2 and fit them with slotted perforations f f, whereby they may be passed around the binding posts B B for the purpose of insertion and removal from the binder.

30 What we claim as our invention is:

1. The combination with perforated leaves of a binding device comprising binder posts engaging said perforated leaves, covers, one of which is fixed to said posts and one is 35 adapted to slide thereupon, and a lock attached to said sliding cover consisting of a channel bar, a plate covering the said channel, lever arms opposed to each other lying within said channel and having engagement 40 with said binder posts and means for actuating said lever arms consisting of an eccentric attached to said channel bar, a yoke engaging said eccentric and adapted to engage the inner ends of the said lever arms whereby 45 the said lever arms may be moved laterally in the same direction to engage the said posts.
2. The combination with perforated leaves of a binding device comprising binder posts 50 engaging said perforated leaves, covers, one of which is fixed to said posts and one is adapted to slide thereupon, and a lock forming the binding part of said sliding cover, consisting of a bar, a channel therein, a plate 55 covering said channel, said bar and plate being perforated to correspond with the position of said binder posts, lever arms lying within said channel, the outer ends of which are adapted to engage said binder-posts and 60 the inner ends having coöperation with each other, elongated slots fixed in said lever arms, pins passing through said slots and fixed rigidly to said bar and said plate; a yoke adapted to engage the said lever arms

and an eccentric fitted within said yoke 65 whereby the same is adapted to be moved laterally within said channel.

3. The combination with perforated leaves of a binding device comprising binder-posts engaging said perforated leaves, covers, one 70 of which is fixed to said posts and one is adapted to slide thereupon, and a lock forming the binding part of said sliding cover, consisting of a bar, a channel therein, a plate adapted to cover said channel, said bar and 75 plate being fitted with perforations corresponding in position with said binder-posts, lever arms lying within said channel and adapted to engage the said binder-posts, and means for moving said lever arms laterally 80 within said channel, consisting of a yoke engaging the inner ends of said lever arms, and an eccentric lying within said yoke, and means for preventing complete revolution of 85 said eccentric, consisting of a semi-circular slot cut in the face of said plate, and a stud fixed to the face of said eccentric and having engagement with said semi-circular slot.

4. The combination with perforated leaves of a binding device comprising binder-posts 90 engaging said perforated leaves, binding bars, one of which is fixed to said posts and one is adapted to slide thereupon, and a lock forming the binding part of said sliding binding bar, consisting of a bar and channel therein, a plate covering said channel, the said bar and plate being perforated to correspond 95 with the position of the said binder-posts, lever arms fitted within said channel and adapted to engage said binder-posts, covers, and means of connecting the same with the 100 said binding bars, consisting of ears projecting from the said binder bars, the said ears being fitted with longitudinal perforations, a perforated metal strip inclosed within the 105 said binder cover, the outer edge of which perforated strip projects beyond the edge of said binder cover, a longitudinal tubular passage fitted to said outer edge of said perforated strip, and a hinge pin passing through 110 the said perforated ears and tubular passage as aforesaid.

5. The combination with perforated leaves of a binding device comprising binder-posts 115 engaging said perforated leaves, covers, one of which is fixed to said posts and one is adapted to slide thereupon, and a lock forming the binding part of said sliding cover, consisting of a hollow bar, said bar being 120 fitted with perforations corresponding in position with the said binder-posts, lever arms fitted within said hollow bar and adapted to engage said binder-posts, and means for moving said lever arms laterally 125 within said hollow bar and means for protecting desks and other polished surfaces from contact with the said covers, consisting of angle recesses fitted at the edge of said

bars, resilient cushions adapted to engage said angle recesses and to project beyond the outer surfaces of the said bars, and means for fixing said cushions to the said bars from the under-side of said bars, consisting of a headed plug thrust through said cushion from its outer face, said plug being fitted with female threads and a screw engaging

the said female threads from the under-side of said bar.
